DEVICE FOR HOLDING WINDOW SASHES
IN OPEN POSITION

Joseph Celec and Charles J. Celec, Chicago, Ill.

Application November 1, 1946, Serial No. 707,278

4 Claims. (Cl. 292—274)

1

This invention relates generally to improvements in an adjustable keeper or latching device for holding a window sash, which is hingedly secured to the upper portion of a window frame, in an open position.

The main objects of this invention are to provide an adjustable window sash keeper device which is entirely automatic in operation; to provide a device of this character which may be readily and quickly mounted on any hinged window sash and frame regardless of size; to provide a device of this character whereby a window sash which is hingedly secured to the upper portion of the window frame may be securely held open at any desired angle without manual manipulation of the keeper or latch; to provide a device of this character whereby a window hinged at its upper end may be held open by this device and then quickly closed without requiring any hand manipulation of the latching means; to provide a device of this character where the window sash can be latched in an open position or closed by the same movement of the window sash; and to provide a device of this character which is relatively simple in construction and inexpensive to manufacture.

An illustrative embodiment of this invention is shown in the accompanying drawings, in which:

Figure 1 is a front view of our invention shown secured to a window frame and sash, the frame and sash being shown broken away.

Fig. 2 is a sectional view taken on line 2—2 of Fig. 1.

Fig. 3 is a cross sectional view of the device of our invention, taken on the line 3—3 of Fig. 2.

Fig. 4 is a cross sectional view taken on line 4—4 of Fig. 3.

Fig. 5 is a cross sectional view taken on line 5—5 of Fig. 2.

Figs. 6 and 7 are side elevational views, each showing the window sash in dotted outline, in various raised positions and illustrating in dotted outline, the motion of the device of our invention.

In the drawings we disclose generally a window sash 1, having a pane of glass 2 secured therein in the usual manner, the sash being pivotally or swingably secured by hinges 3 within the side and upper frames 4 and 4', respectively, in the conventional manner. As is clearly illustrated in Fig. 1 of the drawings, the upper leaf of the hinge 3 is rigidly secured to the top frame 4' by screws 5, or the like, while the lower leaf thereof is rigidly secured to the top bar 1' of the window sash 1 by screws 7, or the like. This is the usual type of window sash and frame found in basements.

The device of our invention comprises an L-shaped arm, preferably constructed of metal, the long leg 8 of which is provided with spaced apertures 9 and 10 to receive the wood screws 13 for rigidly securing the arm to the side bar 1" of the sash 1. The short leg 11 extends at right angles

2

to the leg 8 and is provided with an aperture 12.

A normally vertically disposed swinging link arm 32 has an aperture 33 adjacent the upper end thereof which is adapted to receive a headed bolt 34, which is threaded through the aperture 33 and the aperture 12 of the leg 11 whereby to pivotally secure the arm 32 to the leg 11. The bolt 34 is provided with a nut 35 and a washer 36 positioned one on each side of the arm 32 to secure the arm 32 to the leg 11 and provide a bearing therefor respectively. A horizontally disposed bearing rod or pin 37 is integrally secured adjacent the lower end of the arm 32 in any suitable manner such as by welding, riveting or the like. The pin 37 extends laterally and at right angles to the link arm 32.

A horizontally disposed elongated U-shaped bracket 14 (see Figs. 3, 6 and 7) also preferably constructed of metal is provided with a pair of feet 15 and 16 at the open end thereof, each disposed at right angles to the bracket 14. Each foot 15 and 16 is provided with an aperture through which wood screws 18 and 19 respectively are threaded to rigidly secure the bracket 14 to the side window frame 4".

An adjustable sliding metal block 20 is adapted to fit loosely between the arms 14' and 14" which forms a guideway or slideway 17 therefor. The block 20 is securely held within the slot 17 by a guide bar 21, which is substantially equal to the width of the bracket 14, and which is positioned on the right-hand side of the bracket 14. A vertically positioned rack or latch plate 22, having teeth 23 therein, is positioned on the left-hand side of the bracket 14 and extending above and below the top and bottom side thereof, as viewed and clearly illustrated in Fig. 4 of the drawings. A headed bolt 24 having a nut 25 thereon is threaded through suitable aligned apertures 26, 27 and 28 contained in the latch plate 22, slide block 20, and guide bar 21 respectively, whereby said block 20 is slidably secured within the slideway 17. A pin or rivet 29 threaded through suitable aligned apertures 30 and 31 contained in the latch plate 22 and slide block 20 respectively, holds the latch plate 22 rigidly in a vertical position as shown especially in Figs. 3 and 4 of the drawings. The teeth 23 on the latch 22 are upwardly directed and diagonally disposed on the forward edge of the latch plate 22 whereby to form a plurality of notches 23.1 which face the sash 1. The top and bottom of the latch 22 are each provided with diagonally disposed rounded ends or cam-like surfaces 22.1 and 22.2 respectively.

The pin 37 of the arm 32 is aligned with the latch plate 22 and is adapted to seat in the notches 23.1.

In operation the latch plate 22 is slid into the desired position on the bracket 14 by adjusting the sliding block 20 and securing it to the bracket 14 by tightening the nut 25 on the bolt 24. The window sash 1 is then raised inwardly

and upwardly to the position shown in full lines in Fig. 6. It will be seen that the rod 37 abuts against the cam-like surface 22.2 of the latch plate 22. By further movement of the sash (to that shown in dotted lines in Fig. 6) the rod will automatically move upwardly on the cam-like surface 22.2 and along the inner face edge of the latch plate 22 and seat itself in a notch 23.1 and hold the sash in the position selected.

It will be apparent from examining Figs. 6 and 7 of the drawings that as the sash 1 is further raised at any time the pin 37 will also automatically slide out of the notches 23.1 until said pin passes over the cam-like surface 22.1 (see dotted line disclosure in Fig. 7) and swings behind (or to the right as shown in Figs. 6 and 7) the latch plate 22, whereby to become disengaged from the latch plate 22 and allowing the sash 1 to be closed against the window frame. It will be clear that as the notches 23.1 are upwardly inclined the pin 37 is easily disengaged therefrom by merely lifting the sash 1 upwardly.

It will also be apparent that the point at which the latch plate 22 is secured to the bracket 14 will depend entirely on the length of the link arm 32. If, as shown in the drawings, the link arm 32 is substantially equal to the over-all length of the latch plate 22 then the latch plate 22 will be anchored to a point substantially in the center of the bracket 14. However, if the link arm 32 is shorter than the latch plate 22, the latch plate 22 will be anchored closer to the sash 1 and if the link arm is longer than the latch plate 22, the latch plate 22 will be anchored farther away from the sash 1. It will be equally clear then even though one link arm 32 is used the latch may be secured in various positions to the bracket 14 thereby to adjust the degree to which the window may be maintained in open position.

It is to be understood that numerous details may be altered or omitted without departing from the spirit of this invention, as defined by the following claims:

We claim:

1. A latch device for holding a window sash in open position and wherein the window sash is hingedly secured to the window frame at its upper end comprising a link arm adapted to normally lie in a vertical plane substantially parallel to the plane of the sash when it is in closed position, the upper end of said arm being hingedly secured to and adjacent one edge of the window sash, a bracket adapted to be secured at one end to the window frame immediately adjacent said link arm and below the hinged upper end thereof to project outwardly from said window frame substantially perpendicularly thereto, a latch plate, means adjustably securing said latch plate on said bracket at different distances from the plane of said window frame, said latch plate having diagonally extending notches therein, said latch plate being disposed transversely on said bracket and parallel to the plane thereof, and a stud on the free end of said link arm disposed at right angles thereto and substantially parallel to the hinge axis of the link arm and adapted for cooperative engagement with the notches on said latch bar.

2. A latch device for holding a window sash in open position and wherein the window sash is hingedly secured to the window frame at its upper end comprising a link arm adapted to normally lie in a vertical plane substantially parallel to the plane of the sash when it is in closed position, the upper end of said arm being hingedly secured

to and adjacent one edge of the window sash, a bracket adapted to be secured at one end to the window frame immediately adjacent said link arm and below the hinged upper end thereof to project outwardly from said window frame substantially perpendicularly thereto, a latch plate, means adjustably securing said latch plate on said bracket at different distances from the plane of said window frame, said latch plate having downwardly inclined notches therein opening out of an upright edge of said latch plate facing the window sash, said latch plate being disposed transversely on said bracket and parallel to the plane thereof, and a stud on the free end of said link arm disposed at right angles thereto and substantially parallel to the hinge axis of the link arm adapted for cooperative engagement with the notches on said latch bar.

3. A latch device for holding a window sash in open position and wherein the window sash is hingedly secured at its upper end to and within said frame comprising an arm adapted to be secured at one end to said sash, a link arm pivotally secured at one end to said arm and depending therefrom normally to lie substantially parallel to the plane of the sash when it is closed, a bearing rod integrally secured to the other end of said link arm and extending at right angles thereto substantially parallel to the pivotal axis of said arm, a bracket adapted to be secured at one end to said frame and adjacent said link arm below the pivot point of said arm to project outwardly from the plane of the window frame substantially perpendicularly thereto, a block slidably mounted in said bracket, and a rack plate secured to said block for movement toward and away from the plane of the window frame, means for securing the block in said bracket in any one of a plurality of adjusted positions, and positioned transversely thereof with the rack in an upright position whereby to be engaged by said bearing rod.

4. A latch device for holding a window sash in open position and wherein the window sash is hingedly secured within and to the upper end of said frame comprising an L-shaped arm, one of the legs of said L-shaped arm being adapted to be rigidly secured to said sash, a link arm having one end thereof pivotally secured to the other leg of said arm, a stud integrally secured to the face of the free end of said link arm and extending outwardly therefrom substantially parallel to the pivotal axis thereof, a U-shaped bracket, the open end of said bracket being adapted to be rigidly secured to said frame below the pivot point of and adjacent said arm, a block positioned in said bracket and adjustable toward and away from the ends of said bracket, a guide bar, a rack plate, said guide bar and said plate being positioned one on opposite sides of said bracket with the rack plate in an upright position and facing the window frame, and clamping means engaging the rack plate, block, and guide bar to clamp the same fixedly to the bracket in any one of a plurality of adjusted positions.
